UNITED STATES PATENT OFFICE.

HERMANN LEMP, OF LYNN, MASSACHUSETTS, ASSIGNOR TO GENERAL ELECTRIC COMPANY, A CORPORATION OF NEW YORK.

STEERING-CHECK FOR AUTOMOBILES.

No. 833,281.

Specification of Letters Patent.

Patented Oct. 16, 1906.

Application filed May 23, 1905. Serial No. 261,854.

To all whom it may concern:

Be it known that I, HERMANN LEMP, a citizen of the United States, residing at Lynn, county of Essex, State of Massachusetts, have 5 invented certain new and useful Improvements in Steering-Checks for Automobiles, of which the following is a specification.

This invention relates to the steering mechanism of automobiles, and especially to the automatic check which prevents the steering-wheels from being deflected by a rut or other obstruction in the road and yet permits them to be moved freely by the driver of the car. The so-called "hydraulic" steering- 5 checks have a piston mounted in a closed liquid-filled chamber and provided with valves to permit the liquid to pass from one side of the piston to the other when said piston is vibrated.

The general type of steering-check to which this invention is applicable is shown in my prior patent, No. 725,457, April 14, 1903. In that patent there is disclosed a controlling-finger inside the check-casing, which moves 5 in unison with the steering-finger and actuates a rocker which opens that one of the two valves in the piston which lies on the side toward which the finger moves.

The check which forms the subject of the present invention has no controlling-finger in the body of the check moving in unison with the steering-finger. In place of it I provide an upright plunger for actuating the rocker, which lifts the valves from their seats. Furthermore, the rocker-arm fingers, that lift the valves, are preferably magnetized in order to hold the valves closed without using springs. Moreover, both valves are positively lifted at the same time instead of only one on the advancing side of the piston. There are certain advantages in all these features, which will be pointed out later on.

In the accompanying drawings, Figure 1 is a side elevation of an automobile equipped with my improved steering-check. Fig. 2 is a side elevation of the check on a larger scale. Fig. 3 is a plan view of the same. Fig. 4 is a central vertical section of Fig. 2. Fig. 5 is a cross-section on the line 5-5, Fig. 4. Fig. 6 is a vertical section on the line 6-6, Fig. 4; and Fig. 7 is a vertical section on the line 7-7, Fig. 4.

The automobile may be of any style desired. In Fig. 1 a tonneau machine is shown having the body 1, the driving-wheels 2, and

the steering-wheels 3. A vertical steering-shaft 4 is connected by an arm 5 and a rod 6 with the arm 7, pivoted on the steering-check. The latter comprises a stationary casing 8, provided with lugs 9, by means of which it is secured to the stationary front axle 10 or 60 other suitable support. Mounted eccentrically within the casing is a piston 11, whose end 12 is made concentric with the axis of vibration of said piston. The space between the end 12 and the adjacent wall of the casing is 65 filled in by a segmental block 12^a, which has its inner face curved concentrically with the center of movement of the piston and its outer surface curved to fit the wall of the casing. The upper and lower faces of the piston 70 are flat planes of revolution, the lower one fitting the bottom of the casing and the upper one fitting the under surface of a horizontal diaphragm 13, which rests on a shoulder in the wall of the casing. The upper compartment thus formed in the casing forms a reservoir for the liquid which fills it and also fills the lower compartment on both sides of the piston. The casing has a cover 14.

Formed integral with the piston is an upright cylindrical tubular hub or shaft 15, which has a bearing in the bottom of the casing and also in a sleeve 16, rising from the diaphragm 13. The upper end of the hub extends above the top of the casing and has 85 secured to it a lever 16', whose hub fits over the top of the hub 15 and forms a bearing for the arm 7. The lever 16' has a forked outer end, and in each branch 17 of the fork is mounted a spring-buffer 18, the two pressing 90 against opposite sides of a steering-finger 19, projecting from the hub of the arm 7. The lever 16' is connected by rods 20 with the steering-wheels.

A rock-shaft 21 extends lengthwise of the lever 16' and is journaled in bearings thereon. At its outer end the rock-shaft has an arm 22, pivotally connected with the steering-finger 19. The inner end of the rock-shaft passes into the hub of the lever and is provided with a head 23, having a flattened portion, whose side edges 24 form two tappets resting on the top of a plunger 25, so that in whichever direction the shaft is rocked one of said tappets will depress the plunger, which passes down 105 through the tubular hub of the piston. The lower end of said plunger rests on an arm of a rocker 26, pivoted on a transverse pin 27 in a

chamber in the piston and having on the side opposite said arm two upwardly-projecting fingers 28, registering with valves 29, preferably ball-valves housed in pockets in the piston. The sides of said pockets are cut away to admit the liquid, and their bottoms form beveled seats for the valves. The pockets open downwardly into the chamber in the piston 1, in which the rocker 26 is located, said 10 pockets and chamber forming a passage-way through the piston from one side to the other.

The valves may have springs 30 resting on them to hold them to their seats, as indicated by the dotted lines in Fig. 6. In addition to 15 this or in lieu thereof I may make the fingers 28 or the balls themselves, or both, of tool-steel and magnetize one or both, so that when at rest they will be securely held to their seats by the magnetic attraction and there 20 will be less likelihood of their being accidentally opened by the jarring of the car on a rough road.

The operation of my invention is as follows: The parts stand normally as shown, 25 the steering-gear being locked by the liquid on each side of the piston. When the steering-handle is moved, it first swings the steering-finger 19 laterally against one of the spring-buffers, which yields and permits the 30 finger to rock the shaft 21. This causes one of the tappets 24 to depress the plunger, thereby lifting both valves off their seats and opening a passage for the free flow of liquid from one side of the piston to the other. This 35 unlocks the steering-gear, so that it can be moved by the continued movement of the steering-finger. When the latter is brought to rest, the spring-buffers restore the parts to their normal position, in which the valves are 40 closed and the steering-gear locked. It will be seen that the lever and steering-finger may be shifted angularly with reference to the piston to a considerable extent without modifying the action of the rock-shaft and plunger, 45 since the latter coincides substantially with the axis of the hub of the piston. This provides for displacement due to hard bumps, which in other forms of steering-checks are liable to throw them out of order. More- 50 over, by opening both valves positively the action is more prompt, since if only one valve is opened positively the other must be lifted by the current of liquid. If the springs are rather strong, as they ought to be to resist 55 any jarring of the car, the back pressure may cause a leakage of the liquid out of the casing by way of the piston-hub.

What I claim as new, and desire to secure by Letters Patent of the United States, is—
50 1. In a steering-check, the combination with a casing, of a piston having a tubular hub and valve-seats, valves on said seats, a longitudinally-movable plunger passing axially through said hub, and connections between 65 said plunger and said valves.

2. In a steering-check, the combination with a casing, of a valved piston therein, a lever attached to said piston, a rock-shaft on said lever, and connections between said shaft and the valves in said piston. 70

3. In a steering-check, the combination with a casing, of a valved piston therein, having a tubular hub, a lever attached to said hub, a rock-shaft on said lever extending transverse to said hub, and connections from 75 said shaft through said hub for operating the valves.

4. In a steering-check, the combination with a casing, of a valved piston therein having a tubular hub, a lever attached to said 80 hub, a rock-shaft on said lever extending transverse to said hub, a plunger in said hub in operative relation to said shaft, and valve-operating means actuated by said plunger.

5. In a steering-check, the combination 85 with a steering-finger, of a lever pivoted concentrically therewith, a rock-shaft on said lever having an arm engaged by said finger, a piston movable by said lever, and valves in said piston movable by said shaft. 90

6. In a steering-check, the combination with a casing, of a piston therein having a tubular hub, a lever attached to said hub, a rock-shaft on said lever having a head in line with said hub, a plunger in said hub adapted 95 to be depressed by said head, valves in said piston, and connections between said valves and said plunger.

7. In a steering-check, the combination with a casing, of a piston therein having a tubular hub, a lever attached to said hub, a steering-finger pivotally mounted above said lever, a rock-shaft on said lever having an arm engaged by said fingers, a head on said shaft having a flattened portion, a plunger in 100 said hub having its upper end engaged by said head, and valves in said piston operatively connected with said plunger.

8. In a steering-check, the combination with a piston having a tubular hub and provided with valves, of valve-operating mechanism passing lengthwise through said hub, and means for actuating said mechanism arranged transversely to the upper end of said hub. 110

9. In a steering-check, the combination with a piston having a tubular hub and provided with valves, of a valve-operating plunger passing lengthwise through said hub, and a plunger-actuating element in contact with but not attached to the upper end of said plunger. 120

10. In a steering-check, the combination with a piston having a tubular hub and provided with valves, of a valve-operating plunger passing lengthwise through said hub, a 125 steering-lever attached to said hub, and plunger-actuating means carried by said lever and so connected with said plunger as to be operative irrespective of angular displacement of said lever. 130

11. In a steering-check; a valve held to its seat by magnetic attraction.
12. In a steering-check; a valve, a spring for seating the same, and a magnetized ele-
5 ment attracting said valve to its seat.
13. In a steering-check, the combination with a piston, of a ball-valve, and a rocker having a steel magnetized finger for operating said valve.
14. In a steering-check, the combination

with a piston, of a ball-valve, and a rocker having a steel magnetized finger for operating said valve.

In witness whereof I have hereunto set my hand this 20th day of May, 1905,

HERMANN LEMP.
